UNITED STATES PATENT OFFICE

MORRIS KASSER, OF SAN FRANCISCO, CALIFORNIA

EGG TREATMENT MACHINE

Application filed September 19, 1930. Serial No. 483,038.

This invention relates generally to machines for cleaning eggs preparatory to marketing the same. It has particular application to machines of this character which utilize a sand blast or equivalent means for scouring the surfaces of the eggs.

It is an object of the invention to devise a machine of the above character which will have a relatively high capacity, which will be efficient in its cleaning action, and which will minimize breakage of the eggs.

It is a further object of the invention to devise an egg cleaning machine which will operate with a minimum amount of power for its capacity and which will deliver the eggs substantially free of dust.

Further objects of the invention will appear from the following description in which the preferred embodiment of the invention has been set forth in detail in conjunction with the accompanying drawings. It is to be understood that the appended claims are to be accorded a range of equivalents consistent with the state of the prior art.

25 Referring to the drawings:

Figure 1 is a side elevational view in cross section, illustrating a machine incorporating the present invention.

Fig. 2 is a cross sectional view taken along the line 2—2 of Fig. 1.

Fig. 3 is a cross sectional detail of the means which I prefer to utilize for supporting and for progressing eggs thru the machine.

Fig. 4 is a cross sectional detail taken along the line 4—4 of Fig. 3.

The preferred form of the invention which has been illustrated in the drawings consists generally of a housing 10 which can be made of suitable material such as sheet metal. This housing has been represented as including side vertical walls 11 and 12, end walls 13 and 14, and bottom wall 16. By means which will be presently explained eggs to be treated are passed thru housing 10, and while within the housing they are subjected to the scouring action of a sand blast.

As means for causing the eggs to progress thru the housing in the machine, I employ a structure formed by spaced parallel members 17, such as structural steel angle members,

which extend longitudinally of the housing. These angle members can project thru the end walls 13 and 14 as shown in Fig. 2. As shown more clearly in Fig. 3, other angle members 18 are secured to members 17, and members 18 are connected by spaced cross bars 19. Supported upon bars 19 are a plurality of egg supporting tracks, each of which has been designated generally at 21. As a suitable practical embodiment, each track is shown formed of spaced parallel bars 22, provided with a covering 23 of suitable resilient material, such as resilient vulcanized rubber. Bars 22 can be conveniently retained upon cross members 19 by means of spring clips 24, and they normally extend parallel to the side angle members 17 and longitudinally of the housing 10. They are also properly spaced so that each track 21 will support a row of eggs as shown in Fig. 3, with each egg having two supporting points of contact.

In order to insure a proper progression of the eggs along tracks 21 I provide a plurality of spaced bars 26, which are adapted to extend between and segregate the eggs as shown in Fig. 4. These bars are likewise preferably provided with a covering 27 of resilient material, such as resilient vulcanized rubber. The ends of bars 26 are preferably secured to spaced links 28 of the conveyor chains 29. Angles 18 serve as guide means for chains 29, whereby when these chains move in synchronism at a predetermined speed, bars 26 are likewise progressed at a predetermined speed longitudinally of the housing and above the parallel tracks 21. Chains 29 can be part of an endless conveyor and are driven at a suitable rate from any convenient source of power. Thus in Figs. 1 and 2 the lower loops of the conveyor chains are shown guided by angle members 31, and are also shown engaging sprockets 32.

When the machine is in operation bars 26 move continuously across the track 21, as for example from left to right as viewed in Fig. 2. If an operator, or suitable charging means, places eggs upon the tracks between the bars 26 at the left hand end of the machine, these eggs will be caused to progress thru the housing along the tracks 21 until

finally delivered at the right hand end. As the eggs progress thru the housing they roll continuously by virtue of contact with rods 22. Whether or not the eggs are propelled or rolled by gravity along tracks 21 depends upon whether or not these tracks are horizontal or inclined. If tracks 21 are horizontal then the eggs are propelled by contact with rods 26. In the preferred embodiment of 10 the invention, as illustrated in Fig. 2, tracks 21 are preferably inclined with respect to the horizontal, so that the eggs roll by gravity. Rods 26 therefore merely serve as retaining means to insure a predetermined rate 15 of rolling movement of the eggs. However whether the eggs are propelled or permitted to roll by gravity, in either case each egg will have three points of contact, one point being with one of the rods 26, and the other two 20 points being points of support upon the corresponding track 21.

The means for subjecting the eggs to the action of the sand blast preferably consists of a propeller 33, which is mounted to rotate 25 in a plane parallel to and immediately above the tracks 21. To provide means for rotating this propeller at a relatively high speed, it is shown mounted directly upon the shaft of an electric motor 34. The motor can be 30 protected from the deteriorating action of sand particles by enclosing the same within a housing 36. In order to properly confine the action of propeller 33, it is shown surrounded by cylindrical ring 37, this ring 35 being carried by the walls of housing 10. To continuously supply sand particles to propeller 33, a downwardly convergent structure or funnel 38 surrounds the shaft of motor 34, and the lower end of this funnel is provided with an opening 39. Mounted upon and depending from the apex of funnel 38 there is a flared or conical shaped member 41. Member 41 overlies propeller 33 and is concentric with respect to cylindrical member 37. Sand introduced into funnel 38 flows downwardly thru opening 39 and into the path of movement of the blades or the propeller 33. The inclined blades of the propeller strike or bat the sand particles, thus 45 propelling them with great force downwardly upon the exposed surfaces of the eggs. After striking the surfaces of the eggs, the sand particles drop down thru the egg supporting tracks 21, and are received within a 50 collecting chamber 43. For returning this sand to the funnel 38, I have shown a bucket conveyor 44 disposed upon the back side of housing 10. The box or housing 46 for conveyor 44 is arranged at its lower end to receive sand from collector 43. At the upper end of the conveyor 44, the sand is delivered upon an inclined plate 47 which is provided with a suitable sifting screen 48. The sifted sand is thus returned to funnel 38.

After the machine has been in operation for a considerable time the sand tends to accumulate a considerable amount of foreign matter which has been removed from the eggs, and which is present chiefly in the form of a fine dust. To continually remove such dust from the sand as it accumulates, I have shown a cylindrical shaped conduit 51 extending horizontally above screen 48. Arranged within conduit 51 are the fan blades 52, which are mounted upon shaft 53, this shaft being driven by suitable means such as an electric motor 54. The lower side of conduit 51 is in communication with the space above screen 48 thru opening 56, while one end of the conduit is in communication with the exhaust conduit 57. With motor 54 in operation a current of air is continuously exhausted thru conduit 57, and this current of air carries away lighter dust particles in suspension.

To review operation of the complete machine, an operator or suitable charging means places the eggs to be cleaned between the bars 26, at that end of the machine where the bars are entering the housing. As the eggs progress thru the housing they continuously roll upon the tracks 21. Propeller 33 is driven at a high rate of speed by motor 34 and sand is continuously supplied to the propeller by operation of the bucket conveyor 44. As the eggs roll through the zone lying immediately beneath propeller 33, they are subjected to the scouring action of sand particles batted or propelled by contact with the blades or propeller 33. The sand blasting zone is of sufficient width that each egg has each portion of its surface exposed to the action of the sand a plurality of times. Due to the fact that dust and other foreign particles are continuously exhausted thru conduit 57, the sand is kept relatively clean, and after the eggs have passed thru the sand blasting zone they are substantially free of dust.

It will be evident that my machine will have a relatively high capacity, because of the manner in which the eggs are progressed thru the machine upon a plurality of parallel tracks. It is also characteristic of my machine that its operation requires a relatively small amount of power compared to its capacity. This result is attained by use of the propeller 33, which imparts velocity to the sand particles by virtue of actual mechanical impact with the particles, rather than by attempting to propel the sand particles at high velocity in suspension with rapidly moving air currents. Thus with my machine movement of large volumes of air at high velocity is obviated. The use of propeller 33 is also advantageous in that the propelled sand particles do not move in parallel paths toward the eggs. In fact the particles of sand are propelled along paths at different angles with respect to a plane extending longitudinally of the tracks and coinciding with the axis of

rotation of the propeller. Therefore as a particular egg enters one side of the sand blasting zone, it is subjected to the scouring action of sand particles which scours not only the intermediate portion of the egg, but also one end of the egg. As the egg enters the other side of the sand blasting zone, the surfaces of the other end are effectively scoured by virtue of the fact that the sand particles are now striking the egg from a different angle.

As has been previously explained, the use of inclined tracks 21 is preferred, and has been found to materially contribute to the successful operation of the machine. For example if in progressing thru the machine a mass of foreign material upon the surface of the egg comes into contact with the adjacent surface of the corresponding bar 26, no jamming will result, as the bar 26 will merely withdraw from the egg a sufficient distance to permit the obstruction on the egg to pass. If the eggs were propelled by the bars, such a mass of foreign material upon the surface of the eggs might cause jamming with resultant breakage.

I claim:

1. In an egg treatment machine, a plurality of parallel tracks arranged whereby eggs supported thereby may roll along each track while supported thereon at opposite points along the length of each egg, egg engaging means arranged adjacent said tracks and adapted to move along a predetermined path parallel to the tracks, said engaging means serving to segregate each egg of each row of eggs on a particular track, whereby as said means is moved the eggs continuously roll along the tracks, and means for cleaning the surfaces of the eggs as the eggs are rolled along and supported by said tracks.

2. In an egg treatment machine, means for conducting a plurality of eggs along a predetermined path, the conducting means including parallel track members spaced apart to support each egg at two points in its length and means for sand blasting said eggs while they are advanced along said path, said sand blasting means comprising a propeller arranged adjacent said path, and means for feeding sand to said propeller whereby impact of the propeller with the sand particles serves to forcibly propel the particles upon the supported eggs whereby the eggs are forcibly scoured.

3. In an egg treatment machine, a housing, a plurality of parallel egg tracks extending laterally thru said housing, each track being adapted to support a row of eggs, egg engaging means associated with said track, a plurality of spaced parallel bars adapted to extend laterally of said track, endless conveyor means connected to the ends of said bars whereby said bars are repeatedly advanced in one direction along the upper side

of the tracks, and means within said housing for subjecting eggs upon said tracks to a sand blast.

In testimony whereof, I have hereunto set my hand.

MORRIS KASSER.
